United States Patent

Des. 240,711
Patented July 27, 1976

240,711

COMBINED BOTTLE AND CLOSURE

John D. Angleman, Brookside, N.J., and Doris Du Cret,
New York, N.Y., assignors to Bristol-Myers Company,
New York, N.Y.

Filed Jan. 9, 1975, Ser. No. 539,755

Term of patent 14 years

Int. Cl. D9—01

U.S. Cl. D9—10

FIG. 1 is a perspective view of a combined bottle and closure embodying our new design;

FIG. 2 is a top plan view;

FIG. 3 is a bottom plan view; and

FIG. 4 is an elevational view showing a modified form of our new design showing an opaque closure.

We claim:

The ornamental design for a combined bottle and closure, as shown and described.
